UNITED STATES PATENT OFFICE.

ARMINE ROTH, OF WASHINGTON, DISTRICT OF COLUMBIA.

SHAFT-STRAIGHTENER.

1,322,267.

Specification of Letters Patent. Patented Nov. 18, 1919.

Application filed August 4, 1919. Serial No. 315,064.

To all whom it may concern:

Be it known that I, ARMINE ROTH, a citizen of the United States, residing at Washington, in the District of Columbia, have invented new and useful Improvements in Shaft-Straighteners, of which the following is a specification.

This invention relates to machinists' or mechanics' implements for straightening shafts and shafting and, more specifically stated, consists in an implement of the kind mentioned which is especially adapted for use on shafting and the like which cannot be conveniently taken down and put in a straightening machine. My implement is portable, simple and cheap to manufacture and can readily be disassembled for transportation or storage and assembled again at the place of use.

It is illustrated in the accompanying drawing, in which,

Figure 1 is an elevation of the device shown as applied to the straightening of a line shaft *in situ*, and

Fig. 2 is a similar view taken at right angles to Fig. 1 and showing the device as straightening a shaft in a lathe.

As shown in these views, the device consists of a pair of side plates 1, held together in parallel spaced relation by a head 2 and bolts 3, the edges of the plates and of the head being notched at 4 and 5, respectively, to fit each other. Near their free ends the plates are slotted at 6 to receive the key 7, the function of which will be described later on.

Head 2 has an internally threaded bore in which engages the screw 8, the head 9 of which is provided with openings 10 for the handle 11. The end 12 of the screw has a swivel connection with the work-engaging block 15, by reason of the screw 14 engaging in the groove 13, turned in the screw 8. The end of the latter is convex and the bottom of the bore in the block 15 is concave to permit the block a slight play to seat itself on the work 27. The block 15 has a loose slid-

ing fit between the plates 1 for the same reason.

16, 16, are a pair of similar work-engaging blocks, slidably mounted on the flanged head 21 of a block-carrier 20, which is removably held between the plates 1, 1, by means of the key 7, before mentioned, the bottom edge of the carrier being centrally slotted to fit 55 over the upper edge of said key. The blocks 15 and 16 have V-shaped grooves 23 in their adjacent faces to engage the work.

In Fig. 1, the work, held in the V-grooves 23 of the blocks 15 and 16, is a line shaft 27 60 supported in bearings 25 from a ceiling 26, for example, while in Fig. 2, it is a shaft 27 supported on the centers 28, 28, of a lathe.

One of the advantages of my device is its ready adaptability for use in ordinarily 65 inaccessible places, and another is its portability and the convenience with which it can be disassembled and reassembled. By withdrawing the key 7, the carrier and block 1 can be removed and, if desired, the screw 70 8 can be released from the block 15, by retracting the screw 14, and removed from the head block 2.

Having thus described my invention, what I claim is—

A shaft straightener, comprising a U-shaped frame provided with slots in its legs and a threaded hole in its head, a key fitting in said slots and notched to engage the ends thereof, a block-carrier adapted to be passed 80 between said legs and being notched to engage the upper edge of said key, the upper edge of said block-carrier being thickened or flanged to form a run-way, a pair of work-engaging blocks slidably mounted on said 85 runway and being of less thickness than the space between said legs, an opposing work-engaging block slidably mounted between said legs, and a screw engaged in said threaded hole and operatively connected 90 with said opposing block.

In testimony whereof I have hereunto set my hand.

ARMINE ROTH,
